UNITED STATES PATENT OFFICE.

JOHN D. LINDSLEY, OF KANSAS CITY, MISSOURI.

PIANO-LOADING APPARATUS.

1,101,644.

Specification of Letters Patent. Patented June 30, 1914.

Application filed January 22, 1912, Serial No. 672,780. Renewed August 4, 1913. Serial No. 782,931.

To all whom it may concern:

Be it known that I, JOHN D. LINDSLEY, a citizen of the United States of America, residing at Kansas City, in the county of Jackson and State of Missouri, have invented certain new and useful Improvements in Piano-Loading Apparatus; and I do hereby declare that the following is a full, clear, and exact description of the invention, such as will enable others to make and use the same, reference being had to the accompanying drawings, forming a part of this specification.

The invention has for its object: First, the loading and unloading of movables of great weight, such as pianos and organs, with the expenditure of minimum power by a single person. Second, a traveling elevating support for the piano, requiring a minimum degree of power to lift the piano for transportation.

The invention consists in the novel construction and combination of parts, such as will be fully described and then specifically pointed out in the claims.

In the drawings: Figure 1. is a view, in perspective, of a transfer truck, having a low bed for moving heavy objects, showing the load binding lifting jacks upon the truck, the piano being shown in dotted lines, also showing the skid and elevator, the skid being in an elevated position. Fig. 2. is a longitudinal, vertical, sectional view, taken through the platform or bed of the truck, the skid and elevator, the position of the skid and its load before being raised by the elevator being shown in dotted lines. Fig. 3. is a transverse, sectional view of the platform or bed of the truck, taken on the line x, x , on Fig. 2. Fig. 4. is a view, in perspective, of the forward end portion of the skid. Fig. 5. is a view, in perspective, of one of the piano elevating jacks, taken from the outer side of the jack. Fig. 6. is a front view of the lower, outer side-portion of the jack, as seen in Fig. 5. Fig. 7. is a view, in perspective, of the lower, inner side-portion of the jack, showing the piano-lifting lugs. Fig. 8. is a vertical, sectional view of the lower portion of the jack, taken on the line of Fig. 6. Fig. 9. is a detail view of the locking device for the lower end of one of the brace rods on the bed of the truck, showing a portion of the bed. Fig. 10. is a view, in perspective, of the wheel blocking device for the jacks upon the platform or

bed of the truck. Fig. 11. is a detail view of dog and catch for the jack on the piano-supporting frame of the truck.

Similar numerals of reference indicate corresponding parts in all the figures of the drawings.

Referring to the drawings, 15 indicates a four-wheeled platform vehicle or truck for the moving of objects or articles of considerable length, such as pianos and similar musical instruments, whose weight is to be overcome and over which care is to be exercised, to prevent injury to the instrument in transit. The truck consists of a platform 16, extending horizontally the length of the vehicle, and of the requisite width. The forward axle 17, of the truck, is supported by the wheels 18, and upon said axle is a swivel bar 19, upon the outer ends of which 75 bar is mounted the respective elliptic springs 20 (see Fig. 3).

22 indicates suspension bars connected at their lower ends with the longitudinal outer surfaces of the platform 16 and extended in an upward direction, and thence bent at right angles and extended in an outward direction and secured to the upper leaves of the respective elliptic springs at 23. The rear axle 24 is supported by the wheels 25, and upon said axle adjacent the said wheels are mounted the blocks 26 (see Fig. 2), to which blocks are secured the respective elliptic springs 27. 28 indicates suspension bars for the rear end of platform 16 which are precisely the same as the bars 22, the upwardly and outwardly bent portions of said bars being secured to the upper leaves of the elliptic springs 27. Upon these bars 22 and 28 is supported the platform 16, of the truck, 90 its position being below the lines of the upper leaves of the elliptic springs, and at the same time a considerable distance above the plane of the respective axles 17 and 24. At the forward end of the platform is shown a dash board 29. A short distance in rear of the dash-board is a seat 30, its side supports 31 extending downwardly to and integral with the platform 16, in a vertical line with the outer longitudinal portions of 105 said platform.

Extending transversely through the rear portions of the side supports 31, to seat 30, a short distance upwardly from the lower ends of said supports is a windlass shaft 32, upon the outer, squared end of which shaft, 110 on the right hand side of the truck, adja-

cent to the outer surface of the support 31, is a ratchet wheel 33, and upon the outer surface of the platform 16 is a long pawl 34, engaging with the ratchet wheel 33. Upon 5 the same end of shaft 32 having ratchet wheel 33, is a crank arm 35. Upon the upper surface of the platform 16 are parallel guide rails 36, extending in the longitudinal direction of the platform from its rear end 10 forwardly to within a short distance of a line extending transversely through the rear portions of the supports 31, to the seat 30. These rails are located at short distances inwardly from the line of the longitudinal 15 outer surfaces of platform 16. Near the ends of the rail 36 on the left-hand side of the platform 16, are the standards 37 and 38, respectively, secured rigidly at their lower ends to the platform 16, and extending 20 upwardly in line with the outer, vertical surface of said rail. To the upper ends of said standards is connected rigidly the respective ends of a connecting-bar 39, the standards and bar forming a frame of the 25 desired height to support the piano when loaded upon the truck. Upon the ends of the horizontal bar 39 are suitable sleeves 39*, secured adjustably in position by the set screw 39°. This sleeve carries a staple 39°, 30 and a spring plate 39°; (see Fig. 11).

40 is a brace bar extending from the forward end of bar 39, on standard 37, to the right-hand side of the platform 16, and secured rigidly thereto in the right-hand side 35 of the guide rail 36, upon said side of the platform.

41 indicates a movable rod connected pivotally at its upper end to an eye 42, on the rear end of bar 39. The lower end of rod 41 is bent at right angles at 43, and to said bent 40 portion is pivotally connected at 44, a turn-button 45. The bent portion 43 and button 45 is inserted within a staple 46, on the right-hand side of platform 16, and the 45 right-hand side of truck rail 36, on said side, the button 45, when turned as seen in dotted lines in Fig. 9, retaining the bent end of said rod within the staple. Upon the lower surface of the platform 16, upon a vertical line 50 extending through the platform 16 and the track rails 36, are secured the upper ends of the semi-circular plates or hangers 47, the curved portions of the hangers being inwardly as respects each other. Upon the 55 upper surfaces of the lower ends of these oppositely-positioned hangers, which are in series spaced apart the requisite distance, are track bars 48, extending in the longitudinal direction of the platform 16. Upon 60 said lower surface of platform 16, in line transversely with the forward ends of the track rails 36, is secured a block 49, to the lower surface of which block is secured the forward end of a spring-catch plate 50, hav- 65 ing a barbed rear end or hook 50°.

51 indicates the skid, which consists of parallel angle bars 52, of the proper length to afford an easy, inclined plane from the ground to the bed of the truck, and as shown are trussed at 52°. The vertically-positioned 70 portion of the angle bars 52 constitute the guide rails, and are of a height proportional to the height of guide rails 36, on the platform 16 and a like distance apart. Transverse connecting bars 53 are connected at 75 their respective ends with the lower, horizontal portions of the angle bars, the forward bar 53 being positioned a short distance in rear of the forward ends of the angle bars. The ends of this bar 53 are extended upwardly on the outer surfaces of the angle bars a short distance, as seen in Fig. 4, and then bent at right angles and extended outwardly a short distance, thence bent 80 downwardly to form a U-shaped lug 54. 85 Upon the transverse bar 53, on the rear ends of the angle bars, are similarly formed lugs 54. To the lower surfaces and forward ends of the angle bars 52 are secured the hinge eye plates 55, and on the lower surface and 90 rear end of platform 16 are eye plates 56, beneath each track rail, seen in Fig. 2, within which, adjacent to the eye plates 55, transversely through the eye plates 55 and 56, is a rod 57, which secures the skid temporarily 95 to the platform 16. To the forward, lower, horizontal portions of the angle bars 52, of the skid, are secured the eye-bolts 58. These bolts are bent from beneath the angle bars 100 upwardly, past the free end of said bars, the eye extending upwardly for engagement with an elevating device 60. This device consists of standards 61, having outwardly-extended flanges 62, at their lower ends. A horizontal bar 63 is provided with transverse portions or arms 64, near the outer ends of said bar, and to which bars at the point of intersection of bars 64, the flanges 62, on the standards 61, are connected. 105 These bars and standards form a movable frame extending in height slightly above the plane of the platform 16, of the truck. Upon the upper ends of the frame 60 is a windlass, composed of a transverse rotary shaft 65, journaled in the upper ends of standards 61, upon the outer, squared end of which shaft, adjacent to the outer surface of the standard 61, is a ratchet wheel 66, and upon the standard 61 is a lug 67, and upon 110 said lug is a pawl 68, engaging with the teeth of ratchet wheel 66. With the shaft 65 is connected the inner ends of separate winding and skid elevating ropes 69 and 70, wound upon shaft 65, the outer ends of said ropes being provided with hooks 71. A 115 brace bar 72 extends from one standard 61 to the other standard 61, beneath the shaft 65, the ends of the bar being forked at 73, and said forked ends secured to the stand- 120 ards. 125 130

74 indicates the lifting jack for raising the piano and enabling the piano to be moved upon the skid to the truck. The jack consists of upright standards 75, to the inner surface and lower ends of which standards are secured the ends of a transverse plate 76, (see Fig. 5). The standards extend upwardly about the ordinary height of top of keyboard of a piano from its base and to 10 said upper ends of the standards, directly above the plate 76, is secured the ends of a plate 77. To the inner face portions of the plates 76 and 77 on the right-hand side of the jack, are secured the plates 78, which extend from the outer ends of plates 76 and 77 inwardly to a point intermediate the ends of the respective plates, and are beveled at 15 79. These plates are intended for taking up the space at the ends of the pianos which are 20 drawn inwardly adjacent the keyboard, when the jacks are applied to the ends of the piano. To the outer surface of the lower plate 76, adjacent the standards 75, are secured the flat plates 80, upon the lower ends 25 of which plates are slotted shaft hangers or bearings 81 (see Fig. 8), extending a considerable distance downwardly below the line of the lower edge of the plate 76, and in which bearings is a rotary shaft or axle 30 82, and upon the ends of which shaft directly beneath the standards 75, are rollers 83.

83^x are notches in the lower ends of standards 75, at outer ends of the plates 76 and 78, 35 to admit the rollers 82 and permit the lower edge of plate 76 to come closely in position to the floor.

84 are fulcrum plates, perforated at 35, at their lower ends to admit loosely the shaft 40 82, these fulcrum plates being located adjacent to and a short distance inwardly from the respective plates 80, carrying the slotted hangers or bearings 81.

Two levers, 86 and 87, composed of angle 45 bars, are pivoted at 88, at their outer ends to the respective standards 75, upon a line horizontal with the upper edge of the plate 76, and with the vertical angle of which bars the upper ends of the fulcrum plates 84 are 50 pivotally connected at 84^x (see Fig. 6). The inner ends of the angle bars 86 and 87 extend inwardly and overlap each other. In the lever bar 86 is a slot 89, and in the bar 87 is a pin 90, movable in slot 89. Upon the 55 outer face of plate 76 immediately behind the lever bars 86 and 87 and the slotted portion 89, is a spring hook or catch 91, which engages with the upper surface of the lever bar 86, when both bars are in the same horizontal plane. Upon the lower, inner surface 60 of the plate 76 are short angle plates or lugs 92, the lower angle of the plate or lug extending horizontally from the line of the lower edge of said plate (see Fig. 7).

65 93 is a grasping rod, secured at its ends

within the U-shaped clamps 94, to the outer surfaces of the standards 75, a short distance downwardly from the upper ends of said standards, and below a line horizontal with the lower edge of plate 17, its office being to 70 enable the piano to be shifted to the right or left.

95 is a hook secured to the outer surface of the lower plate 76, near its lower edge, and 96 is a hook on plate 77, on the left-hand side of the jack, and 96^x is a double hook secured to the same side of plate 77 intermediate the ends thereof. Upon the outer surface and upper end of standard 75 is pivoted a hook 77^x. This hook engages with 80 the staple 39^a, on the sliding sleeve 39^x, on bar 39, when the jack is mounted on the truck and makes a firm connection of the jack with the frame, these devices being at both ends of the frame. 85

97 indicates a chock for the wheels 83, of the jack 74, and consists of a bar 98, to the lower surface and ends of which are secured the blocks 99, having inclined forward ends 100 (see Fig. 10). To the lower surface of 90 the bar 98, intermediate the blocks 99, is secured a block 101, through which extends an opening 102, transverse to the bar 98. In the opening 102 is a hook 103, having a screw-threaded stem 104, upon which stem 95 is a thumb nut 105. With the rotary shaft 32, of the windlass, beneath the seat 30, at the forward end of the truck, is connected one end of a traction-imparting rope or cable 106, of the desired length, which is 100 wound upon said shaft 32, and its free end extended through a pulley 107, connected with the upper surface of the platform 16, beneath shaft 32, the cable being adapted to be extended in length the full length of the 105 truck and skid, and upon said free end of the cable is a loop 108. Upon the upper surface of the platform 16, a short distance in rear of the supports 31 for the seat 30, is a transverse fixed block 109, the rear surface being 110 inclined at 110, said bar acting as a chock to the piano or like object in its forward position on the platform.

In the operation of loading the truck with the piano, the skid 51 is connected with the 115 end of platform 16, of the truck, at its inner end, and the outer end resting upon the ground, as seen in dotted lines in Fig. 2, the rod 41 being drawn aside to the left. The cable 106 on the windlass shaft 32, is unwound from said shaft and its free end extended a considerable distance past the line of the outer ends of skid 51. The piano to be loaded upon the truck being adjacent to the outer ends of the skid 51, one of the jacks 120 74 is placed in position with the inner surfaces of plates 76 and 77, close in contact with the one end of the piano, and the grasping lugs 92 extended beneath the lower surfaces of one end of the piano, in which posi- 125 130

tion of the jack the lever bars 86 and 87 are freed from the catch 91 and in an elevated position as seen in Fig. 6. Downward pressure being applied to the lever 86, the shaft 82 carrying the rollers 83, which is on the upper portion of the slotted bearing 81, moves downwardly to the lower portion of the bearing, and when the lever bars reach the position seen in Fig. 5, the spring catch 91 secures the lever arms. In this movement of the lever arms the end of the piano provided with the jack is elevated in position, and its weight at said end is borne by the rollers 83. At the other end of the piano is placed another jack 74, in precisely the same manner, and operated to raise the said end and support the same upon the rollers 83, of the companion jack. Straps 74° are passed lengthwise the piano in front, and their ends made fast to the double hooks 96°, on the respective jacks, and a strap 74° passed in rear of the piano and its ends also connected with the double hooks 96°. Another strap is extended over the top surface of the piano and its ends connected with the hooks 96, on the respective jacks, as seen at 96°, in Fig. 1, these straps being shown in dotted lines in Fig. 1. Still another strap 97° is passed around both jacks and the piano just above the plate 76. The hook 108, on the free end of the traction cable 106, is passed beneath the piano and engaged with the hook 95, on the plate 76 of the jack, upon the outer end of the piano. The rollers 83, upon the jack 35 on the inner end of the piano, are then placed on the skid and between the guide rails formed by the vertical portions of angle bars 52. The crank 34, on the windlass shaft 32 is then operated to wind the cable 40 on said shaft, and with the exercise of the power transmitted through the cable the piano is moved upon the skid and into the position seen in dotted lines in Fig. 2. A movable elevating frame 60 is then placed adjacent to the outer ends of the skid 51, and the hooks 71, on the elevating ropes 69 and 70, are engaged with the eye bolts 58, on the outer ends of the angle bars of the skid. The weight of the piano now being held by the rope or cable 106, on the skid, and the pawl 35 in engagement with the ratchet wheel 33, the crank 34 is now removed from the end of the shaft 32 and placed upon the squared end of the elevating shaft 65, on the elevator frame 60, and power applied through said shaft to wind the ropes 69 and 70, thereby raising the outer end of the skid 51 with the piano as its load comes into a horizontal position as seen in Fig. 1. The ratchet wheels 66, on shaft 65, being held by the pawls 68, the crank 34 is detached from shaft 65, and placed upon the shaft 32, and the winding movement on the cable 106 continued moving the piano upon the platform 16, of the truck, the wheels 83 passing be-

tween the guide rails 36. This movement is continued until the wheels 83 on the jack, on the forward end of the piano, come into contact with the chock block 109, on the platform 16.

The chock is placed in position adjacent to the wheels 83, on the jack, on the outer end of the piano, the inclined blocks 100 preventing a rear movement of the wheels. The hook 103 on the chock block is now engaged with the eye bolt 103°, on the rear end of bed 16 of the truck, thereby holding the truck and piano firmly to the bed. Upon turning of the nut 105 on the hook 103, the draw is made on the chock with sufficient power to cause the blocks 100 to be forced against and bend the rollers 83, and thus prevent any longitudinal movement of the piano on the truck. The rod 41, which has been moved aside to permit the movement of the piano, is then engaged with the staple 46, on the platform 16, as before. The hook 77 on the truck frame is then engaged with the staple 39 on the sliding sleeve 39, the spring 39° engaging with the hook to prevent withdrawal from the staple. The elevator frame 74 is now moved from the outer end of the skid, and the rod 57 removed from the end of the platform, releasing the eye plates 55, on the forward end of the skid. The end of the skid is now placed upon a line with the lower surface of the platform 16, and the lugs 54 placed on the track rails 48, on the hangers 47, and the skid moved longitudinally between the hangers in the direction of the forward end of the truck until the forward, transverse bar 53 is engaged by the hook catch 50, on the block 47, on the bed of the truck, in which position the skid is held from movement until its service is again required. In the position of the piano upon the platform of the truck, the frame formed by the bars 37, 38 and 39 prevents lateral movement of the piano, and if preferred the rear strap upon the piano may be extended past the standards 37 and 38. The suspension of the platform 16, upon the elliptic spring affords ample protection from shocks occasioned by ruts or obstacles in the road, and affords a resiliency in any swaying movement occasioned by uneven roads.

The invention affords means for moving other objects besides pianos, of like adaptability, to be handled and held by the jacks, such as boxes of large size and of such weight as to cause difficulty in hauling, and which usually requires a number of persons to successfully move.

My invention enables one person to move a piano from one point to another and place it in position, whenever needed, without any aid but that of the apparatus, and this alone is economy in the cost of removal of such instruments, as well as expediting such removal as has been practically demonstrated

in a complete apparatus. In unloading the truck of its piano or other object, the operation as heretofore described is reversed, the skid being raised first, at its outer end, and 5 the weight lowered to the ground, the delivery being accomplished with safety and the necessary expedition.

Such modifications of the invention may be employed as are within the scope of the 10 appended claims.

Having fully described my invention, what I now claim as new and desire to secure by Letters Patent is:

1. In a truck, the combination with the 15 platform, of hangers upon the lower surface thereof, oppositely-positioned skid-supporting track bars carried by the hangers, a skid, and lugs carried by the skid movably engaged with and supporting the skid on the 20 track bars.

2. In a truck for carrying loads, the combination with the platform of the truck, of 25 hangers on the lower surface thereof, oppositely-positioned skid carrying track bars supported by the said hangers, a skid, and lugs on the skid movable upon and supporting the skid on the track bars, and a catch 30 on the truck for holding the skid from longitudinal movement.

3. In a truck for carrying loads, the combination with the platform of the truck, of 35 hangers on the lower surface thereof, oppositely-positioned skid-supporting track bars supported by said hangers, and a block connected with the lower surface and forward end portion of the said platform, and a spring-plate on the said block having a barbed rear end portion.

4. In a truck for carrying loads, the combination with the platform of a truck, of a 40 windlass, a cable operated by the windlass, a transport for the load on the platform, and

wheels supporting the transport, a transversely-positioned chock-carrying bar in rear of the transport, and chock blocks carried by said bar, and an adjustable securing means on the chock-carrying bar connected with the bed of said truck. 45

5. In a truck for carrying loads, the combination with the platform of the truck, of a 50 windlass, a cable operated by the windlass, a transport for the load on the platform, and wheels supporting the transport, a transversely-positioned chock bar in rear of the transport, and chock blocks carried by 55 said bar, and a hook having screw-threaded stem carried by said bar, and an adjusting nut on said stem.

6. In a truck for carrying loads, the combination with the platform of the truck, of 60 a vertical frame carried by the platform, and a detachable rod pivotally connected with the frame, and a staple on the platform, said rod having a bent end portion engaging with the staple, and a turn button 65 on said bent end portion of the rod.

7. In a piano wagon, the combination with an upright frame on the wagon and a horizontal bar forming a part of said frame, of a movable sleeve on said bar, and a staple 70 on said sleeve, a piano truck, and a hook on said truck engaging with said staple.

8. In a piano wagon, the combination with an upright frame on the wagon, and a horizontal bar on said frame, of a staple on 75 said sleeve, and a spring plate beneath the staple, a piano truck, and a hook thereon engaging with the staple on the horizontal bar and adapted to be retained by said spring plate.

JOHN D. LINDSLEY.
